FIG. 1

FIG. 2

FIG. 3

FIG. 4

FIG. 5

FIG. 1 is a top front perspective view of a combination heater and stove, shown in the heating position, showing my new design;

FIG. 2 is a similar perspective view showing the combination heater and stove in its alternative cooking position;

FIG. 3 is a view in rear elevation of the combination heater and stove in the heating position of FIG. 1;

FIG. 4 is a bottom plan view of the combination heater and stove in the heating position of FIGS. 1 and 3;

FIG. 5 is a top plan view of the combination heater and stove in the heating position of FIGS. 1, 3, and 4.

The end of the combination heater and stove which is not shown is identical in appearance to the end which is shown in FIGS. 1 and 2.

I claim:

The ornamental design for a combination heater and stove, substantially as shown and described.
